METHOD OF MAKING ELECTRICAL CONTACTS
Childress B. Gwyn, Jr., Export, Pa., assignor, by mesne assignments, to Talon, Inc., a corporation of Pennsylvania

Filed Nov. 16, 1960, Ser. No. 69,639
1 Claim. (Cl. 29—155.55)

The present invention relates to processes for making projection welding type composite contacts, and more particularly to such contacts in which a steel backing member is indented and has elements of contact element material placed therein.

A highly satisfactory type of electrical contact is one having a backing or support of relatively hard material, such as steel, with one face of this backing or support carrying a contact made of silver or the like. Such a contact is shown in my prior Patent No. 2,199,240.

Several methods are known by which the above described contact can be made. In one known method, a button is provided by blanking and forming a contact from a sheet of clad or overlay material. That is to say, the initial sheet may comprise steel with an overlay of silver. The contact produced by this method is of satisfactory quality, but the method has many disadvantages, among which are a high scrap loss. In addition, in this method, tolerances, materials temper and ratios of component materials must be held to very exacting limits. These requirements further increase the cost of the end product, so that all in all, this process is a relatively expensive one.

In another known process, the backing metal members are first blanked or formed from steel strip, are then electroplated with nickel, copper or the like, where desired, and then subsequently deposited into refractory boats or jigs. The desired contact facing material, such as silver, is then blanked from a sheet and placed upon the surfaces of the steel backing members, which are usually disks, and then the refractory boat or jig, loaded as described, is heated in an oven in order to fuse the silver contact element to the steel backing member. This process, which is described in my Patent No. 2,049,771 has been found to require a relatively large heating source, because of the refractory boat or jig. Since these boats or jigs generally are made of or contain carbon or graphite mixtures, the steel backing members absorb some of the carbon, and this results in embrittlement, blistering, peeling, etc. In addition, it has been found that the contact facing material does not uniformly flow over the surface of the backing member, in all cases, and this results in final products which have only a thin facing of contact material near the outer edges thereof.

An object of the present invention is to provide a process for manufacturing composite contacts of satisfactory quality with economy of cost.

Yet another object of the present invention is the provision of a process for making composite contacts in which the use of refractory boats or jigs is eliminated.

A further object of the present invention is to provide a process which will require the consumption of less heat than heretofore in order to manufacture composite contacts.

A still further object of the present invention is the provision of a process for making composite contacts which will avoid the absorption of carbon or graphite, and thereby eliminate the production of contacts that are brittle, subject to blistering, peeling, etc.

2

Another object of the present invention is to provide a process for making composite contacts in which the contacts produced will have a suitably thick and uniform facing of contact material.

Other objects and many of the attendant advantages of the present invention will be readily understood from the following specification and drawings, wherein:

FIGURE 1 is a plan view of a blank of weldable base material prepared in accordance with the invention.

FIGURE 2 is a cross-sectional view showing the deposition of a contact element in the sheet of FIGURE 1.

FIGURE 3 is an enlarged cross-sectional view of the structure shown in FIGURE 2, after heating.

FIGURES 4 through 8 are cross-sectional views illustrating successive steps in the removal of an individual contact from the backing material strip.

FIGURE 9 is a cross-sectional view of the product produced by this process.

FIGURE 10 is a cross-sectional view of the positioning of parts for the manufacture of a composite contact in accordance with another embodiment of the process of the present invention.

FIGURES 11, 12 and 13 are views showing successive steps in the treatment of the parts shown in FIGURE 10, for the formation of a composite contact, before heating.

FIGURE 14 is a cross-sectional view of the intermediate structure of the composite contact resulting from the step illustrated in FIGURE 13.

FIGURE 15 is a view similar to FIGURE 14, but showing the structure after heating.

FIGURES 16 and 17 show steps in the process illustrating the removal of a composite contact from the base material sheet.

Referring now to the drawings, wherein like or corresponding reference numerals are used to designate like or corresponding parts throughout the several views, there is shown in FIGURE 1 a sheet 20 of weldable base material, such as steel. Sheet 20 may be of any length, and in practice the length of sheet or strip 20 is limited only by production and transportation factors. The sheet 20, which will be understood to be a blank, has therein a plurality of indentations 21, the indentations 21 being produced by known embossing or coining operations and being circular in the embodiment shown. There are a great number of the indentations 21 provided in the sheets 20, so that production may proceed at a rapid rate.

Referring now to FIGURE 2, there may be seen in cross-section a part of the sheet 20, the indentation 21 being shown as having placed therein a button or contact element 22 which is, conventionally, of silver. Whatever the materials of the sheet 20 and element 22, it will be understood that the element 22 will have a lower melting point than the sheet 20. It will be observed that the bottom wall 23 of indentation 21 has a central depression 24 and a peripheral depression 25.

The entire sheet 20, or a suitable portion thereof, is, after being loaded with the elements 22, passed into a furnace, the heat of which melts the element 22, and after cooling there is obtained a structure having the configuration shown in FIGURE 3. It will be noted that the element 22 has melted and has filled the indentations 24 and 25, and that the silver element 22 has crept up the walls of the indentation 21 as is indicated at 26. There is also a convex upper surface 27 of the melted and solidified element 22.

Subsequent to the removal of the sheet 20, or a portion thereof, from the furnace, the steel grip may be passed

to a conventional punch press where the individual indentation 21 with the melted and solidified element 22 will come under a punch 30 which is above a coining die 31 in a die body 32. Punch 30 and die body 32 will be caused to move towards each other viewing FIGURE 4, the action continuing as shown in FIGURE 5 wherein it may be seen that the punch 30 has moved into contact with the sheet 20, entering into the indentation 21, while the coining die 31 has moved into position to receive that material which will be punched from the sheet 20, and comprising the melted and solidified contact element 22, together with the indentation bottom wall 23.

FIGURE 6 shows the shearing action completed, with separation of the parts from sheet 20 and FIGURE 7 shows the further progression of punch 30 which now compresses the sheared element 22 and bottom wall 23 against the coining die 31 in die body 32. FIGURE 8 shows the upward movement of punch 30, and the downward movement of coining die 31, carrying with it the completed composite contact 35. Contact 35 is shown in FIGURE 9, after having been removed from the coining die 31 as by blowing or the like, and may be seen to comprise a backing member 36 having a central button 37, to the upper surface of which is fused a generally arcuate silver contact element 38, it being understood that the element 38 was formerly the element 22 and that the backing member 36 formerly was the bottom wall 23 of indentation 21.

It will be understood, of course, that while the upper surface of element 38 is shown convex, and that this is due to the shape of the punch, 30, this shape is given by way of illustration only and where other shapes are desired the punch 30 may be provided with such other shapes.

Referring now to FIGURES 10 through 17, there is shown a further process in accordance with the invention, there being seen in FIGURE 10 a sheet 40 which may be of steel or the like, which sheet 40 is a backing member and is positioned between a die body 32 containing a coining die 31 and a die body 42 having an opening 43 therethrough. Above the die body 42 having an opening 43 therethrough, above the die body 42, and conveniently placed in contact therewith, is a sheet 45 which may be of silver or other suitable contact element material. In alignment with the aperture 43 and the coining die 31 is a punch 30.

The punch 30 is caused to descend, as is shown in FIGURE 11, so that it engages the sheet 45, and in passing through the aperture 43 shears a disk or button 46 from the sheet 45. The completed shearing action of the disk 46 is shown in FIGURE 12, where the punch 30 has continued its downward movement. Still carrying before it the disk 46, the punch 30 approaches and engages the backing sheet 40, and causes an indentation in the backing sheet 40, as is shown in FIGURE 13. This indentation 47 has the disk 46 therein, and because of the co-action and shape of the punch 30 and the coining die 31, the sheet 40 will be embossed or coined to provide the above dimensioned indentation 47. As will be understood, while the punch 30 moves downwardly, the coining die 31 will move upwardly as is indicated by the arrows in FIGURES 11, 12 and 13.

Subsequent to the action and positioning of the parts as shown in FIGURE 13, the silver disk 46 will have the position and shape shown in FIGURE 14 in the indentation 47. It will be noted that the silver disk 46 is pressed into and against the metal of the indentation 47, and with this having been obtained the entire sheet 40, or a suitable portion thereof, is placed in a furnace to thereby heat the silver disk 46 to its melting point, so that after melting and resolidifying, the silver disk 46 will have the configuration shown in FIGURE 15, where it may be seen that there is a creeping up the walls of the indentation 47 of the periphery of the silver, as is clearly shown at 48.

There may also be provided a convex surface, centrally located, as at 49. It will be understood that the partially completed product shown in FIGURE 15 is essentially the same as that shown in FIGURE 3, and that thereafter there may be effected the same separating and coining operation as is shown in FIGURES 4 through 8.

Alternatively, it is in some instances desirable to continue the downward motion of the punch 30 from the position shown in FIGURE 13, so that the disk 46 and the part of sheet 40 which it overlies and is in contact with are completely separated from the sheet 40, this being shown in FIGURE 16. The punch 30, having completed its punching operation is shown moving upwardly while the coining die 31 is shown moving in a downward direction. Continued movement of the coining die 31 will carry it and the disk 46 and the part of sheet 40 to which it is adhered by pressing in a downward direction so that these parts are beneath the die body 32 (FIGURE 17). Thereafter, the partially formed composite contact is removed from the coining die 31 and is heated in a furnace so that the disk 46 melts and thereby is fused to the backing member 50.

In the process above disclosed, due to the fact that the indentations may be made and loaded in such large quantities and with such great rapidity as is provided by fast operating punching machines, the production of composite contacts may proceed at an extremely rapid rate. This will substantially reduce the cost of the end product. Further, since it is unnecessary to provide jigs or boats which will consume heat and contaminate the contact elements, there is a further advantage in the economy of production and quality of the end product.

It will be obvious to those skilled in the art that various changes may be made without departing from the spirit of the invention and, therefore, the invention is not limited to what is shown in the drawings and described in the specification, but only as indicated in the appended claims.

I claim:

- 40 A process for making projection welding composite electrical make-and-break contacts which comprises:
  - (a) superposing a silver contact facing material blank and a weldable steel base material blank in spaced substantially parallel relation;
  - (b) moving at least one punch having a convex central protuberance and a convex peripheral protuberance through said contact facing material blank to shear a contact facing element therefrom, said facing element being simultaneously deformed to conform to the shape of said punch and including an outer facing having a convex central portion and a convex periphery;
  - (c) moving a coining die toward and into abutment with the side of said base material blank opposite from said contact facing material side;
  - (d) moving said punch toward the base material blank to force said contact facing element into the blank and form an indentation therein, including a bottom wall having a central concave depression formed by and superimposed with the convex central portion of said facing element, and a peripheral concave depression formed by and superimposed with the convex periphery of said facing element;
  - (e) moving said punch away from the weldable base material blank to disengage the punch from the facing element seated in said blank;
  - (f) heating said base material and said facing element to liquefy said facing element and cause the material thereof to flow along the walls of the indentation and fuse to the abutting base material, the surface of the fused facing element remote from the bottom wall of said indentation being convex in shape and having a peripheral edge defining a concave meniscus within said indentation;
- 50
- 55
- 60
- 65
- 70
- 75

(g) moving a concave-shaped punch against each such composite fused element with a force sufficient to shear the same from the base material blank, to provide the desired contact having a facing element of substantially uniform thickness.
